UNITED STATES PATENT OFFICE.

FRED E. GREENE, OF BERKELEY, CALIFORNIA, ASSIGNOR TO A. B. HUMPHREY COMPANY, OF ESCALON, CALIFORNIA. A CORPORATION OF CALIFORNIA.

AIR-CIRCULATING DEVICE FOR REFRIGERATOR CARS.

Application filed April 27, 1927. Serial No. 186,894.

This invention relates to refrigerator cars and especially to means whereby a thermosiphon circulation of air may be promoted and maintained through the fruit and the 5 ice bunkers while the car is in transit.

Since the origin of refrigerator cars, a number of attempts have been made to maintain uniform temperature and adequate refrigeration but without material success. 10 Thousands of dollars have been paid by the carriers to the shippers using refrigerator cars due to the inability of the carriers to maintain the commodity at a sufficiently low temperature to guarantee delivery to the 15 market in good condition. Refrigerator cars ordinarily contain an ice bunker at each end and the fruit or other commodity packed in the car intermediate the bunkers. Sufficient ice to cool the commodity in the storage 20 compartment is available in the bunkers but as no means are provided for maintaining the air in circulation through the bunkers and the commodity, comparatively poor and inefficient refrigeration is the result.

25 It is ordinarily thought that more or less circulation of air is maintained by thermosiphon action. Actual experience, however, has proven that comparatively little, if any, circulation of air takes place as the air cooled 30 by the ice in the bunkers tends to settle in a layer at a rather definite elevation in the lower portion of the car. In fact the height of cool air above the floor has been so definitely determined, that the lugs or boxes containing the fruit or other commodities being 35 transported are seldom stacked above a definite height as spoilage of the commodity will otherwise take place and it has accordingly been common practice to sell the top tiers of 40 fruit separately.

Due to the frequent spoilage of shipments both carriers and shippers have agreed upon standard heights of loading and bracing to secure the best results in transportation 45 across the country, i. e., the load is stacked just so high and is divided into two sections to form a central air passage between the loads, to provide space for a suitable form of bracing which secures the loads against 50 shifting and damage; and furthermore to permit such circulation of air as may take place.

The object of the present invention is to promote and insure thermosiphon circula-

tion of air through the bunkers and the commodity being transported. The invention is shown by way of illustration in the accompanying drawings in which:

Fig. 1 is a central vertical longitudinal section of a standard form of refrigerator 60 car.

Fig. 2 is a cross-section of the refrigerator car.

Referring to the drawings in detail and particularly Fig. 1, A indicates in general 65 a refrigerator car, 2 the bottom or floor section, 3 and 4 the sides and ends respectively and 5 the top or roof section. Disposed at each end of the car are ice bunkers 6 and intermediate the bunkers is a storage compartment generally indicated at B in which the fruit or other perishable commodity to be shipped is packed or stored according to standard practice, to wit, in two separate sections or stacks as indicated at 8 and 9. A 70 central passage 10 is thus formed, between the two sections and this passage is employed to promote thermosiphon circulation of the air and also to provide space for a standard 75 form of bracing such as generally indicated 80 at C. It might also be stated that the load which in this instance is represented by the stacks of lug boxes indicated at 8 and 9 is supported by a false or elevated floor 11 which is constructed of heavy slats. The 85 false floor provided forms a bottom air passage 12 extending from end to end of the storage compartment and this passage is in communication with the lower ends of the ice bunkers through screened openings 13. 90 The upper ends of the bunkers are also provided with screened openings such as indicated at 14 and as previously stated, it is 95 ordinarily supposed that the air will cool and settle downwardly through the ice and as such will flow along the passage 12 and rise 100 upwardly through the commodity and then return by thermosiphon circulation through the upper openings 14 of the bunkers. A slight amount of circulation may take place 105 but it is not sufficient to insure proper cooling or refrigeration of the commodity being shipped, this being best proven by the fact that the lug boxes can only be stacked to a definite height as actual experience has 110 proven that if the lug boxes are stacked above a definite height, the fruit or commodity disposed above that height is almost

certain to spoil. In other words, the cold air settles in the lower portion of the storage compartment and does not rise above a definite height and it is for this reason that it has positively been determined that comparatively little, if any, thermosiphon circulation takes place.

In the present instance, means are provided for promoting and in fact insuring thermosiphon circulation of air. This is accomplished as follows:

- If fruit is being shipped, the lug boxes are stacked on the false floor 11 in two separate piles in the usual manner as indicated 16 at 8 and 9 to form a central passage 10 in which the bracing may be placed. After this has been accomplished according to standard or ordinary practice, it is only necessary to lower a pair of plates such as 20 indicated at 15 and 16 down on top of the load. These plates have a length substantially the same as that of the stacks of lug boxes and they are sufficiently wide to extend from one side wall to the other as 25 shown in Fig. 2. One end of each plate may rest or be entirely supported by the lug boxes as indicated at 17 while the opposite end of each plate is preferably supported by extensive folding legs such as indicated 30 at 18. These legs support the respective plates in an inclined position. After the plates have been lowered and placed in position as shown in Fig. 1, it is only necessary to close and seal the doors of the car and 35 the car is ready for shipment. The moment the doors have been closed, the air in the bunkers is cooled by the ice and as such will settle downwardly and discharge through the openings 13 into the passage 12 which 40 is formed below the false floor 11. The air gradually rises upwardly between the slots and the lug boxes and as such cools the fruit. The air is, of course, raised in temperature by the fruit which is comparatively 45 warm and the increase in temperature will cause the air to rise upwardly in under the plates 15 and as these are positioned on an incline, the air will flow towards the central passage 10 and will then enter the upper 50 portion of the car as shown by the arrows. The cool air settling in the bunkers will, of course, create a slightly evacuated condition in the upper ends of the bunkers and the warm or rising air is thus drawn into 55 the upper ends of the bunkers and thermosiphon circulation of air is started. This circulation will be continuously maintained as long as there is a difference of temperature between the ice and the commodity 60 being shipped. When an equalized temperature is obtained, circulation will, of course, cease but any change in temperature will, of course, immediately start circulation and efficient refrigeration as far as the commodity is concerned is insured. When the 65

car reaches its destination, it is only necessary to break the seal and open the doors. The plates 15 and 16 together with the bracing indicated at C will, of course, have to be removed and the commodity may then 70 be unloaded in the usual manner. In order to facilitate the handling and storage of the plates 15 and 16, means are provided for bracing the plates in under the ceiling or roof of the car for securing the same in this 75 position when unloading and also during return shipment as the cars are usually returned as empties. The means employed for securing the plates in under the ceiling is nothing more or less than ordinary lugs such 80 as indicated at 20 and 21. The lugs 20 are stationary and the ends 17 of the plates are inserted between the ceiling and the lugs 20. The lugs 21 are pivoted as indicated at 22. They are swung to assume a reverse position 85 to that shown in full lines in Fig. 1 when the ends 17 of the plates are lifted into engagement with the lugs 20. The opposite ends of the plates are then raised up into engagement with the ceiling and the lugs 21 90 are then swung or reversed on their pivots and as such will swing in under the plates and secure and support the same. The plates 15 and 16 can in this manner be conveniently 95 handled and stored and as they are placed in the position flush with the ceiling, they will not interfere with the storage capacity of the car if freight is handled when the car is returned. The legs 18 are swung about their pivots to lie parallel with the 100 plates when they are in their reverse position and as such will not interfere with the freight or consume extra space, the legs 18 being held in their extended position when the plates are lowered as shown in Fig. 1 105 by ordinary braces such as shown at 18.

Actual experience has, first, determined that uniform circulation of air is maintained in an upward direction between and through the lug boxes and the central passage 10; 110 secondly, it has been determined that actual thermosiphon circulation takes place; and third, that the lug boxes or commodity being transported may be stacked to a greater height due to the circulation maintained and 115 due to the fact that the comparatively cool air passes over the upper layers of the lug boxes before it can enter the central passage 10 and return to the upper ends of the bunkers; fourth, that the commodity is received at its destination in a better condition; and fifth, that greater loads may be 120 transported than has heretofore been possible.

While certain features of the present invention are more or less specifically described and indicated, I wish it understood that various changes may be resorted to within the scope of the appended claims; similarly, that the materials and finish of 125

the several parts employed may be such as the manufacturer may dictate or varying conditions or uses may demand.

Having thus described my invention, what I claim and desire to secure by Letters Patent is:—

1. In a refrigerator car having ice bunkers at opposite ends and an intermediate storage compartment in which a perishable commodity is loaded in two stacks and braced between the stacks, a portable apparatus for promoting and maintaining a thermosiphon circulation of air through the bunkers and the commodity, said apparatus comprising a cover plate for each stack, said plates having a width substantially equal to the width of the car and having lengths substantially equal to that of each stack, the ends of the plates which are adjacent the bunkers being adapted to be supported by the commodity and means for supporting the opposite ends of the plates in an elevated position with relation to the commodity and means for supporting and securing the plates in under the ceiling of the car.
2. In a refrigerator car having ice bunkers at opposite ends with inlet and outlet openings in each bunker, said inlet openings being adjacent the ceiling of the car and the outlet openings adjacent the floor and an intermediate storage compartment in which a perishable commodity is loaded in two stacks and braced between the stacks, means for promoting and maintaining a thermosiphon circulation through the stacks or commodity and the bunkers, said means comprising a pair of inclined cover members, one over each stack, said cover members having their points of highest elevation at a point adjacent the center of the car and their points of lowest elevation near the bunkers and means for securing said cover members in the inclined position as described to cause air rising upwardly through the commodity to travel towards the point adjacent the center of the car and then to travel outwardly in under the ceiling of the car towards the inlet openings of the bunkers, then to settle downwardly through the ice in the bunkers and finally to return to the commodity at a point below the commodity.

FRED E. GREENE.
